UNITED STATES PATENT OFFICE.

VERNON ROYLE, OF PATERSON, NEW JERSEY.

AUXILIARY WORK-HOLDER FOR EDGING-MACHINES.

1,230,927.

Specification of Letters Patent. Patented June 26, 1917.

Application filed April 30, 1915. Serial No. 25,062.

To all whom it may concern:

Be it known that I, VERNON ROYLE, a citizen of the United States, and resident of Paterson, in the county of Passaic and State 5 of New Jersey, have invented a new and useful Improvement in Auxiliary Work-Holders for Edging-Machines, of which the following is a specification.

My invention relates to a work holder 10 and more particularly to a work holder used as an auxiliary to the main work holder of a plate or block edging or trimming machine for preparing printers' plates or blocks for the press. I have illustrated it 15 in connection with the edging machine which forms the subject-matter of my pending application Serial No. 25,063, filed April 30, 1915.

In the accompanying drawings,

20 Figure 1 is a top plan view of a portion of an edging machine showing the auxiliary holder in the position which it assumes when in use.

Fig. 2 is an enlarged front elevation of 25 the holder.

Fig. 3 is an end view of the same.

Fig. 4 is a horizontal section taken in the plane of the line A—A of Fig. 2.

Fig. 5 is a vertical section in the plane of 30 the line B—B of Fig. 2, and

Fig. 6 is a vertical section in the plane of the line C—C of Fig. 2.

The sliding table of the edger is denoted by 1; this with the work holding clamps, 35 such as shown in my pending application above referred to and denoted in said application by 3 and 4, forms the main work holder. The gage mounted on the table to slide at right angles to the movement of the 40 table is denoted by 2; the gage fence pivoted to swing down onto the table and up and back from the table, by 3; and the cutter, of any well known or approved form, by 4.

In the present instance the same dovetail 45 headed bolts, here represented by 5 and 6, described in my pending application above referred to, for holding the extension pieces in position on the working edge of the fence 3, are employed to secure the auxiliary work- 50 holder in position, this auxiliary work-holder being employed when it is required to hold thin plates in position to be faced.

The body of this auxiliary work-holder, 55 denoted by 7, is of a general oblong shape and of skeleton structure, its back being provided with a shallow tongue 8 to enter

the neck of a dovetail slot in the working face of the fence 3. Openings 9 and 10 extend from the back of the body 7, through to open spaces in the body to receive the bolts 5 and 6, the latter being provided with nuts 11 and 12 and with springs 13, 14, to hold the body 7 yielding to the fence while being slid into the desired adjustment and to clamp it in working position, all as explained in my pending application above referred to in reference to extension pieces.

The front of the body 7 is provided with an undercut groove 15 for the reception of a sliding bar 16, the latter having tongues 70 or ribs 17, 18, for guiding it. The outer face of the bar 16 has a clamping jaw 19, in the form of a thin plate, secured thereto, and the inner face of the bar is provided with a series of spiral teeth 20. A spiral 75 toothed driving pinion 21 is fixed to rotate with a short shaft 22, the teeth of the pinion 21 being engaged with the teeth 20 on the bar 16. The shaft 22 is mounted in suitable bearings in a space 23 in the body 7, 80 and has thereon a worm or screw 24 engaged by a spiral toothed pinion 25 on an upright shaft 26 hung in a boss 27 projecting upwardly from the body 7. A hand wheel 28 locked to the shaft 26, serves to rotate the shaft and through the interconnect- 85 ing gear, slide the bar 16.

A second clamping jaw or abutment 29 is fixed to the outer end of a post 30, seated in a shouldered socket 31 extending through the body 7 from front to back. The rear portion of the post 30 is screw-threaded and a nut 32 engaged with the said threaded portion is held against travel in a slot 33 in the body 7. By turning the nut 32, the post 30 and jaw 29 thereon are adjusted outward and inward to engage the plate 34 to be operated on as near the path of the cutter as may be safely done and hence hold the work firmly while the cutter is operating on it. It will be noted that the adjustable abutment or jaw is at the rear end of the work and receives the pushing thrust of the cutter as the work is advanced.

The holder is a unit and may be readily fitted to other than the specific edger here shown. It is simple and durable in structure and may be relied upon to securely hold delicate plates in position.

What I claim is:

1. The combination with a main work holder, of an auxiliary work holder connect-

ed thereto and provided with a work holding jaw, means for sliding the said jaw relative to the body of the auxiliary holder, an abutment on said auxiliary work holder 5 and means for adjusting the abutment out and in transversely to the sliding movement of the jaw into position opposite the end of said jaw.

2. An auxiliary work-holder comprising 10 a sliding jaw, spiral gear for operating the jaw, an abutment, means for adjusting the abutment laterally with respect to the path of the sliding jaw and means for detachably securing the work-holder to a gage.

15 3. An auxiliary work-holder comprising

a body, a toothed bar carrying a clamping jaw, gear for operating the jaw, a traveling abutment post provided with a screw threaded portion and a nut engaged with said screw-threaded portion and held 20 against a bodily traveling movement in a recess in the body.

In testimony, that I claim the foregoing as my invention, I have signed my name, in presence of two witnesses, this twenty-first 25 day of April, 1915.

VERNON ROYLE.
